Robert A. Miller of Glasgow, Kentucky
Litter's Patent.

The schedule referred to in these Litter's Patent and making part of the same containing a description in the words of the said Robert A. Miller himself of his improvement in the machine for breaking hemp and flax.

To all to whom these presents shall come

Be it known that I, Robert A. Miller of Glasgow in the County of Barren & State of Kentucky, have invented a new and useful improvement in the cleaning and separating hemp & flax from their woody parts, and that the following is a full and exact description of the construction and operation of the said machine as invented & improved by me.

A strong frame is erected by two beams crossing each other at right angles & firmly braced to their uprights, it supports a shaft carrying a wheel from 30 to 112 feet diameter which circulates horizontally (by horse or other power) within one foot of the ground. The lower side of its narrow rim, are fastened right angled triangular rays at their own length apart; an oblong piece 26 inches thick 3 to 4 broad & 9 to 10 long, being cut diagonally forms two such, their acute angles are 16 to 19 degrees, they are shot with hoop iron at least 18 inch. broad.

Four feet diameter around the rim is allowed for the horses path just beyond which rises the uprights of the frame and to that line comes the tails of the breakers their heads extending outward diametrically from the shaft. There are eight breakers to a complete machine, four being breakers and four light cleaners made from a solid piece of black iron 7 feet long 16 inches wide & four thick, their solid heads are six inches long second of the breakers 10 to 15 feet long body eight inches and tails 16 to 18.

© 2023 The breakers have swords 8 inches apart at the body and 2 at the head but the swords of finishing are only half length and 2 inches apart anywhere, on this latter principle 8 hand finishing breakers are made but accidentally any of these in the machine for a moment & to employ the hands within doors during wet weather

Each breaker stands about $2\frac{1}{2}$ feet high upon a frame composed of three pieces a sill 7 feet by 2, & 8 inches thick into which head and tail blocks are firmly set they are 6 inches thick the latter is 2 feet broad & 14 high from $2\frac{1}{2}$ upwards there are 16 inches wide out and in which the breaker plays upon an iron pivot. The former is covered with leather sole stiffened with gunn elastic or curled hair to prevent the destruction of breakers. Grooves in these blocks receive the lower swords or flat, in which they are moveable, to render them efficient in every kind of hemp and to facilitate the cleaning they are 6 inches broad at the head but only 3 at the body

Near the midset of each breaker rests the end of a lively ash spring pole 12 feet long its other end is fastened in two uprights directly under the cog and pointing with the rim when in motion are placed triangular levers with legs $2\frac{1}{2}$ feet long conjoint angle works upon a pivot the legs extending to a right line between the shaft and breaker on which moves the driving lever a straight piece of 8 or more feet long its outer end passing under the lever is at least 14 feet beyond the cog till under the tail of the breaker to which it is yoked by a bow of tough white oak or hickory the in end works upon a pivot & is moveable to adjust the triangular lever to the cog directly under which its lower limb is loosely attached to the driving lever, ditch of one foot broad & deep having been dug & lined with stones and plants for these levers to move in and that part under the lever covered with small platforms

Upon the end of the upper limb of each triangular lever is placed a cast iron friction wheel of 18. to $2\frac{1}{2}$ inches diameter

which remove four fifths of the friction as they roll over the iron faces of the inclined planes of the cog. Three pins rise out of the tail of each brake called regulators because removing the yokes from one to another elevates or depresses the head of the brakes to any desired height over each spring hole is a guard coming out of the tail block, which causes the brake to return from a given elevation. — Each hand is furnished with a rake the pins of which are one foot long with it he occasionally removes the accumulating shovs & by a certain motion brings into one place all that have lost attached to them these hitherto totally lost are left in burdens & obtained in the same manner as hemp. The wheel put into motion each cog in passing the friction which depresses the movable head of the triangle and with them the outer ends of the drawing levers and tails of the brakes, elevating their heads to any regulation height, whence the spring poles and their guards throw them forcibly down again, these propelling by the simple action & reaction of levers for the triangle serve only to remove the drawing levers out of the horses way, they loose power and are wholly unnecessary with steam or water.

Eight hands are the full complement of the machine and move in the following order,

At. Steady upon (say the right side of a brake) and put in his ample of raw hemp moving it steadily at every side of the brake, while the woody parts are chiefly driven out, when he turns to the finisher at the moment C, leaves it and is succeeded by B on the left side with his rough hemp who also turns to his finisher as D just it. Thus alternately & continually occupying the eight brakes without interrupting each other and not performing the work of this engine man by more activity by the labour being small.

The odd cog is necessary to the successive fall of the brakes each pair of which stand diametrically opposite to each other and move simultaneously sounding as one . . .

The four brakes occupy the cardinal points forming a square.

voids of declination and divide time as 1. 2. or a whole are half egs
The finishing stand in the intermediate spaces forming a system also that
upon the line of the greatest possible declination or 145° from the other

The two squares are the algebraic signs of addition and multiplication
being parents of all things of art or science & the four corner stands
this is 1. 2. 4. 8 their arithmetical progression memorializes the
origin of this present vulgar division of inches and their geometrical
that of the scale of Music

The discovery of the last is ascribed to the fabled Pythagoras
who in this manner distinguished the sound of cithara, strings where
the machine is called the Pythagorean harp brake.

To my original invention is now added the improvement
for which also a right is claimed as follows,

1. egs in the form of an inclined plane, 2. cast iron friction
wheels, 3. iron faced egs, 4. stuffed head blocks, 5. Guards
to the spring plates, 6. regulation in the brakes of. movable slate,
and their form, 8. finishing brakes, of equal swordy, both for
the machine and house of cleaning the offal 10. Adjusting the
brake —

One horse moves the eight brakes with ease and sufficient to
forty hundred weight may be cleaned in one day (besides the
offal) according to the weather and the degree of waterizing which
the horse has received
